UNITED STATES PATENT OFFICE.

ZACHARIE B. RICHARD, OF LA FAYETTE, LOUISIANA, ASSIGNOR OF ONE-EIGHTH TO OSCAR KILPATRICK AND ONE-EIGHTH TO WILLIAM DAVIS, BOTH OF LA FAYETTE, LOUISIANA.

PLIERS.

1,090,941.

Specification of Letters Patent. Patented Mar. 24, 1914.

Application filed February 28, 1913. Serial No. 751,347.

To all whom it may concern:

Be it known that I, ZACHARIE B. RICHARD, a citizen of the United States, residing at La Fayette, in the parish of Lafayette and 5 State of Louisiana, have invented a new and useful Pliers, of which the following is a specification.

This invention relates to pliers or clamps for splicing wires, such as are employed by 10 linemen, electricians or other mechanics, artisans for splicing sections of wire or for use in divers other purposes.

The present invention comprehends the provision of means whereby the handles of 15 the pliers may be more conveniently and effectively brought together for splicing the sections of wire, this invention being applicable to ordinary pliers and to pliers embodying reversible handles.

20 As another object, the present invention contemplates the provision of a device of the character indicated which shall be simple, substantial, durable and inexpensive in construction, as well as compact, and which 25 shall be convenient, efficient and simple in its use.

With the foregoing general objects outlined, and other objects in view, which will be apparent as the invention is better understood, the present invention resides in the novel construction and combination of parts hereinafter set forth and claimed, it being understood that this invention may be altered or changed in its details in accordance 30 with the dictates of convenience or efficiency within the scope of the appended claims without departing from the spirit of the invention.

The invention is illustrated in its preferred 40 embodiment in the accompanying drawings, wherein like reference characters have been employed to denote corresponding parts, and wherein:—

Figure 1 is a side elevation of a pair of 45 pliers embodying reversible handles and including the present invention. Fig. 2 is an enlarged fragmental section of the reversible clamping means. Fig. 3 is an enlarged transverse section of the said means. Fig. 50 4 is a perspective view of a cuff employed in carrying out the present invention. Fig. 5 is a side elevation of an ordinary form of pliers embodying the present invention.

Fig. 6 is a fragmental detail of a pair of blacksmith's tongs. 55

Referring specifically to the drawings, particularly to Figs. 1 to 4, inclusive, the handles of the pliers are designated by the letter H, the same being connected at one end by links L and including the jaws J 60 having the notches or recesses N along their opposite faces. The handles H are adapted to be reversed so as to bring the corresponding sets of notches N into coöperation or registration, as is practised and well known 65 in the art. It is the practice at present, to pivot a link to the free end of one handle so that the said link may be swung to either side to engage the other handle when the wires to be spliced are clamped between the 70 jaws. Pliers of this character are more or less difficult to use, for the reason that it requires considerable contractive force upon the handles to bring the handles sufficiently together to permit the engagement of the 75 link with the free handle, and for other reasons which need not be enumerated. This serious objection has been overcome by a novel arrangement for bringing the handles of the pliers together and locking the same 80 in such position; and in carrying out the present invention, the free end of one handle is preferably enlarged as designated by the numeral 6, and is provided with a primary and a secondary reduced portion 7 and 8, re- 85 spectively, which are in the form of a stepped projection. A cuff or collar 10 is rotatably mounted on the reduced portions 7 and 8, the said cuff having the bore 11 and the counter-bore 12 receiving the sec- 90 ondary and primary portions 8 and 7, respectively. The secondary reduced portion 8 is riveted or swaged over the outer end of the cuff 10 in order to retain the cuff in position and to permit same to rotate freely. 95 This cuff 10 is provided with diametrically opposite trunnions 13 at its outer end and apertures 14 diametrically opposite each other at the inner end of the said cuff, the cuff also having transverse channels or 100 grooves 15 at the outer ends of the apertures 14. The cuff 10 is preferably of the same diameter as the enlarged portion 6 so as to present a slightly and neat appearance. A lever 16 is pivoted to the cuff 10, the said 105 lever being U-shaped in cross-section, the

flanges thereof terminating in ears 17 at one end, which ears are in engagement with the trunnions 13. The intermediate portion of the lever 16 is curled backward from between the ears 17 to provide an eye 18, which is spaced outwardly from the pivoted point of the lever. The lever 16 when swung against the outer side of the corresponding handle is adapted to fit over or straddle the handle so as to provide a compact arrangement, the particular shape of the handle presenting a convenient surface for handling same. A U-shaped link 19 is pivoted to the lever 16, the said link having the eyes 20 at its ends, and a pin or rivet 21 passes through the eyes 20 and 18 for providing the pivotal connection of the link and lever. This link 19 has a web 22 connecting its arms and providing a plurality of handle receiving openings 23. In order to lock the cuff 10 in the proper position upon the corresponding handle, a head 25 has been arranged in the radial recess 9 drilled in the portion 7 and is provided with a projecting nib or spur 26 engageable in the apertures 14 of the cuff, a compression spring of coiled wire, designated by the numeral 24, being disposed in the recess 9 behind the head 25 for giving an outward tension thereto. It will therefore follow, that when the cuff 10 is turned to the proper position to bring one of the apertures 14 into registration with the recess 9, the spring 24 will press the nib or spur 26 into engagement with the corresponding aperture so as to constrain or lock the cuff against rotary movement. By inserting any suitable instrument or even the finger in the corresponding channel 15, the nib 26 may be forced inwardly against the tension of the spring 24 so as to disengage the cuff and permit the cuff to be reversed in which event, the nib will engage the other aperture. The cuff is in this manner locked in either position corresponding to the position of the handles H relative to each other, as will be understood.

The use of pliers of this character is well understood in the art and need not be described at length, and it will appear that by swinging the lever 16 outwardly, or in the position indicated in dotted lines in Fig. 1, the link 19 may be engaged to the other or free handle so that when the lever is swung inwardly and against the outer side of the handle to which it is pivoted, the handles will be drawn together to clamp the sections of wire between the jaws J. It will therefore appear, that the handles H need not be drawn together by the application of the hand or hands thereon, but it is merely necessary to engage the link 19 to the free handle and then swing the lever 16 inwardly against the corresponding handle, which provides for increased leverage so that the

handles may be easily and conveniently drawn together. The link 19 being pivoted to the lever 16 outwardly from its pivotal point will cause the lever and link to lock in position when the handles are drawn together, or swing beyond dead center, the lever 16 fitting snugly against the corresponding handle or straddling the same. From the foregoing, it will also be apparent, that when the handles H are reversed, the cuff 10 may be reversed so that the link 19 may be engaged to the free handle to permit the handles to be drawn together. The various openings 23 which engage with the loose or free handle permit the free handle to be engaged in various positions, the said openings being particularly provided when the attachment is employed with various pliers, tongs or the like, so as to enable the properly engage the free handle.

When the invention is to be employed in connection with an ordinary pair of pliers, such as illustrated in Fig. 5, the ears 17 are pivoted to the usual eye E provided at the free end of one handle H' by means of the usual pin P. This form of pliers, as is customary, embodies the jaws J' having the complementing notches N' for receiving the sections of wire when the pliers are used for splicing. It will be readily apparent, that the lever 16 in being swung outwardly permits the link 19 to be engaged with the other or free handle H' so that when the lever is swung inwardly as above described, the handles will be drawn together. The attachment is similar to the one above described, with the exception of the provision for reversing the attachment, which is necessary where the handles are reversible.

Fig. 6 illustrates the end H'' of one of the handles of a pair of pliers or tongs, which is provided with the notch G. This view illustrates how the lever 16 illustrated in Fig. 5 may be detachably engaged to the upper handle H' of the pliers illustrated in the said figure. Supposing the upper handle in Fig. 5 to be provided with a notch G as illustrated in Fig. 6, said notch would be adapted to receive the pin P to permit the link 19 to be engaged over the lower handle H', and to then permit the lever 16 to be swung to locking position, as above stated. The eye E is preferable when the lever 16 is to be permanently attached to the upper handle, while the notch G is preferable when it is desired to permit the lever 16 to be readily applied and removed from the pliers or tongs.

From the foregoing, taken in connection with the drawings, the various uses and advantages of the present invention will be apparent, and it will also be apparent that the objects aimed at are attained in a satisfactory manner, the present invention provid-

ing a desirable device of the character indicated and for the purposes to which it is designed.

Having thus described the invention, what is claimed as new is:—

1. The combination with pivotally connected handles, of a lever pivoted to the free end of one handle and adapted to swing against the outer side thereof, and a link pivoted to the lever and engageable with the other handle.

2. The combination with pivotally connected handles, of a lever having a pair of ears at one end straddling and pivoted to the end of one handle, and a U-shaped link designed to engage the other handle and having its ends pivoted to the lever.

3. The combination with pivotally connected handles, of a lever of U-shaped cross-section, the flanges of which terminate in ears at one end straddling and pivoted to the free end of one handle, the intermediate portion of the lever being curled back from between the ears to provide an eye, a pin passing through the eye, and a U-shaped link designed to engage the other handle and having its ends connected to the said pin.

4. An attachment for pliers, including a lever designed to be pivoted to the free end of one handle so as to swing against the outer side of the handle, and a link pivoted to the lever and engageable with the other handle.

5. An attachment for pliers, embodying a lever having a pair of ears at one end designed to straddle and to be pivoted to the free end of one handle so that the lever may swing against the outer side of the handle, and a U-shaped link engageable with the other handle and having its ends pivoted to the lever.

6. An attachment for pliers, embodying a lever of U-shaped cross-section, the flanges of which terminate in ears at one end adapted to straddle and to be pivoted to the free end of one handle of the pliers, the intermediate portion of the lever being curled back from between the ears to provide an eye, a pin passing through the eye, and a U-shaped link designed to engage the other handle and having its ends connected to the said pin.

7. In combination with pliers embodying reversible handles, of a lever pivotally and rotatably connected to the free end of one handle, and a link pivoted to the lever and engageable with the other handle.

8. In combination with pliers embodying reversible handles, of a rotatable cuff on the free end of one handle, a lever pivoted to the cuff, and a link pivoted to the lever and engageable with the other handle.

9. In combination with pliers embodying reversible handles, of a cuff rotatable on the

free end of one handle and having diametrically opposite trunnions, a lever having ears at one end engaged to the trunnions, and a U-shaped link designed to engage the other handle and having its ends pivoted to the lever.

10. In combination with pliers embodying reversible handles, of a rotatable cuff on the free end of one handle and having diametrically opposite trunnions, a lever of U-shaped cross-section, the flanges of which terminate in ears at one end engaging the said trunnions, the intermediate portion of the lever being curled back from between the ears to provide an eye, a pin passing through the eye, and a U-shaped link engageable with the other handle and having its ends connected to the said pin.

11. In combination with pliers embodying reversible handles, of a cuff rotatable upon the free end of one handle, a lever pivoted to the cuff, a link pivoted to the lever and engageable with the other handle, and means for locking the cuff in reversed positions.

12. In combination with pliers embodying reversible handles, one handle having a reduced portion at its free end, of a cuff rotatable on the reduced portion and having diametrically opposite trunnions, the reduced portion being riveted over the outer end of the cuff, a lever of U-shaped cross-section, the flanges of which terminate in ears at one end pivoted to the said trunnions, the intermediate portion of the lever being curled back from between the ears to provide an eye, a pin passing through the eye, a U-shaped link engageable with the other handle and having its ends connected to the pin, and means for locking the cuff in reversed positions.

13. In combination with pliers embodying reversible handles, one handle having a reduced portion at its free end and a radial recess in the reduced portion, of a cuff rotatable on the reduced portion and having diametrically opposite apertures in its inner end and diametrically opposite trunnions at its outer end, the reduced portion being riveted over the outer end of the cuff and the cuff having transverse channels at the outer ends of the apertures, a head in the said recess and having an outer nib engageable through the said apertures, a compression spring in the recess behind the said head, a lever of U-shaped cross-section, the flanges of which terminate in ears at one end pivoted to the said trunnions, the intermediate portion of the lever being curled back from between the ears to provide an eye, a pin passing through the eye, and a U-shaped link having its ends connected to the said pin.

14. An attachment for pliers embodying a cuff adapted to rotatably engage the end

of one handle of the pliers, a lever pivoted to the cuff, and a link pivoted to the lever and engageable with the other handle of the pliers.

- 5 15. An attachment for pliers embodying a cuff adapted to rotatably engage over the end of one handle of the pliers and having diametrically opposite trunnions, a lever having ears at one end engaged over the
10 trunnions, and a U-shaped link having its

terminals pivoted to the lever and adapted to engage over the end of the other handle of the pliers.

In testimony that I claim the foregoing as my own, I have hereto affixed my signature in the presence of two witnesses.
